[57] CLAIM

The ornamental design for a toy container, substantially as shown and described.

DESCRIPTION

FIG. 1 is a top plan view of a toy container showing my new design;

FIG. 2 is a bottom plan view thereof;

FIG. 3 is a front elevational view thereof, the right and left sides and rear elevational views being identical; and
FIG. 4 is a left-side elevational view thereof, partly in section.

FIG. 1

FIG. 2

FIG. 3

FIG. 4
